Primary Examiner—A. Hugo Word*Assistant Examiner*—Doris V. Coles*Attorney, Agent, or Firm*—Jacobson, Price, Holman & Stern[57] **CLAIM**

The ornamental design for a runner's combined writing pad, pencil and recorder pouch, as shown and described.

DESCRIPTION

FIG. 1 is a front elevational view of a runner's combined pad, pencil and recorder pouch, showing my new design;

FIG. 2 is a top view thereof;

FIG. 3 is a bottom view thereof;

FIG. 4 is a rear elevational view thereof;

FIG. 5 is a left side view thereof;

FIG. 6 is a right side view thereof;

FIG. 7 is a front elevational view in the fully open position;

FIG. 8 is a top view thereof;

FIG. 9 is a bottom view thereof;

FIG. 10 is a left side view thereof;

FIG. 11 is a rear elevational view thereof;

FIG. 12 is a right side view thereof;

FIG. 13 is a front elevational view of the invention illustrated in FIG. 1, with the top portion open for use;

FIG. 14 is a front elevational view of a second embodiment;

FIG. 15 is a rear elevational view of the embodiment illustrated in FIG. 14; and,

FIG. 16 is a front elevational view in the closed position of the embodiment illustrated in FIG. 14.
